(57) **ABSTRACT**

A vertical member, which is preferably a support post used in a molten metal pump, includes a ceramic tube and tensioning structures to add a compressive load to the tube along its longitudinal axis. This makes the tube less prone to breakage. A device, such as a pump, used in a molten metal bath includes one or more of such vertical members.

TENSIONED ROTOR SHAFT FOR MOLTEN METAL

CROSS-REFERENCE TO RELATED APPLICATIONS

This application is a continuation of, and claims priority to U.S. patent application Ser. No. 16/144,873, filed Sep. 27, 2018, and entitled “Tensioned Support Shaft and Other Molten Metal Devices” which is a continuation of, and claims priority to, U.S. patent application Ser. No. 15/406,515 (Now U.S. Pat. No. 10,267,314), filed Jan. 13, 2017, and entitled “Tensioned Support Shaft and Other Molten Metal Devices,” which claims the benefit of U.S. Provisional Application Ser. No. 62/278,314, filed Jan. 13, 2016, and entitled “Tensioned Support Shaft and Other Molten Metal Devices,” the contents of each of the foregoing applications, are incorporated herein by reference, to the extent such contents do not conflict with the present disclosure.

FIELD OF THE INVENTION

The invention relates to tensioned support shafts that may be used in various devices, particularly pumps for pumping molten metal.

BACKGROUND OF THE INVENTION

As used herein, the term “molten metal” means any metal or combination of metals in liquid form, such as aluminum, copper, iron, zinc and alloys thereof. The term “gas” means any gas or combination of gases, including argon, nitrogen, chlorine, fluorine, Freon, and helium, which are released into molten metal.

Known molten-metal pumps include a pump base (also called a housing or casing), one or more inlets (an inlet being an opening in the housing to allow molten metal to enter a pump chamber), a pump chamber of any suitable configuration, which is an open area formed within the housing, and a discharge, which is a channel or conduit of any structure or type communicating with the pump chamber (in an axial pump the chamber and discharge may be the same structure or different areas of the same structure) leading from the pump chamber to an outlet, which is an opening formed in the exterior of the housing through which molten metal exits the casing. An impeller, also called a rotor, is mounted in the pump chamber and is connected to a drive system. The drive shaft is typically an impeller shaft connected to one end of a motor shaft, the other end of the drive shaft being connected to an impeller. Often, the impeller (or rotor) shaft is comprised of graphite and/or ceramic, the motor shaft is comprised of steel, and the two are connected by a coupling. As the motor turns the drive shaft, the drive shaft turns the impeller and the impeller pushes molten metal out of the pump chamber, through the discharge, out of the outlet and into the molten metal bath. Most molten metal pumps are gravity fed, wherein gravity forces molten metal through the inlet and into the pump chamber as the impeller pushes molten metal out of the pump chamber. Other molten metal pumps do not include a base or support posts and are sized to fit into a structure by which molten metal is pumped. Most pumps have a metal platform, or super structure, that is either supported by a plurality of support posts attached to the pump base, or unsupported if there is no base. The motor is positioned on the superstructure, if a superstructure is used.

Cooper, U.S. patent application Ser. No. 13/841,594, filed Mar. 15, 2013, by Paul V. Cooper, and U.S. patent application Ser. No. 14/027,237, filed Sep. 15, 2013, by Paul V. Cooper.

Three basic types of pumps for pumping molten metal, such as molten aluminum, are utilized: circulation pumps, transfer pumps and gas-release pumps. Circulation pumps are used to circulate the molten metal within a bath, thereby generally equalizing the temperature of the molten metal. Circulation pumps may be used in any vessel, such as in a reveratory furnace having an external well. The well is usually an extension of the charging well, in which scrap metal is charged (i.e., added).

Standard transfer pumps are generally used to transfer molten metal from one structure to another structure such as a ladle or another furnace. A standard transfer pump has a riser tube connected to a pump discharge and supported by the superstructure. As molten metal is pumped it is pushed up the riser tube (sometimes called a metal-transfer conduit) and out of the riser tube, which generally has an elbow at its upper end, so molten metal is released into a different vessel from which the pump is positioned.

Gas-release pumps, such as gas-injection pumps, circulate molten metal while introducing a gas into the molten metal. In the purification of molten metals, particularly aluminum, it is frequently desired to remove dissolved gases such as hydrogen, or dissolved metals, such as magnesium. As is known by those skilled in the art, the removing of dissolved gas is known as “degassing” while the removal of magne-

sium is known as "demagging." Gas-release pumps may be used for either of both of these purposes or for any other application for which it is desirable to introduce gas into molten metal.

Gas-release pumps generally include a gas-transfer conduit having a first end that is connected to a gas source and a second end submerged in the molten metal bath. Gas is introduced into the first end and is released from the second end into the molten metal. The gas may be released downstream of the pump chamber into either the pump discharge or a metal-transfer conduit extending from the discharge, or into a stream of molten metal exiting either the discharge or the metal-transfer conduit. Alternatively, gas may be released into the pump chamber or upstream of the pump chamber at a position where molten metal enters the pump chamber. The gas may also be released into any suitable location in a molten metal bath.

Molten metal pump casings and rotors often employ a bearing system comprising ceramic rings wherein there are one or more rings on the rotor that align with rings in the pump chamber (such as rings at the inlet and outlet) when the rotor is placed in the pump chamber. The purpose of the bearing system is to reduce damage to the soft, graphite components, particularly the rotor and pump base, during pump operation.

Generally, a degasser (also called a rotary degasser) includes (1) an impeller shaft having a first end, a second end and a passage for transferring gas, (2) an impeller, and (3) a drive source for rotating the impeller shaft and the impeller. The first end of the impeller shaft is connected to the drive source and to a gas source and the second end is connected to the impeller.

Generally a scrap melter includes an impeller affixed to an end of a drive shaft, and a drive source attached to the other end of the drive shaft for rotating the shaft and the impeller. The movement of the impeller draws molten metal and scrap metal downward into the molten metal bath in order to melt the scrap. A circulation pump is preferably used in conjunction with the scrap melter to circulate the molten metal in order to maintain a relatively constant temperature within the molten metal.

The materials forming the components that contact the molten metal bath should remain relatively stable in the bath. Structural refractory materials, such as graphite or ceramics, that are resistant to disintegration by corrosive attack from the molten metal may be used. As used herein "ceramics" or "ceramic" refers to any oxidized metal (including silicon) or carbon-based material, excluding graphite, or other ceramic material capable of being used in the environment of a molten metal bath. "Graphite" means any type of graphite, whether or not chemically treated. Graphite is particularly suitable for being formed into pump components because it is (a) soft and relatively easy to machine, (b) not as brittle as ceramics and less prone to breakage, and (c) less expensive than ceramics.

Ceramic, however, is more resistant to corrosion by molten aluminum than graphite. It would therefore be advantageous to develop vertical members used in a molten metal device that are comprised of ceramic, but less costly than solid ceramic members, and less prone to breakage than normal ceramic.

SUMMARY OF THE INVENTION

The present invention relates to a vertical member used in a molten metal device. The member is comprised of a hollow ceramic outer shell that has tension applied along a longi-

tudinal axis of a rod therein. When such tension is applied to the rod, the ceramic outer shell is much less prone to breakage. One type of vertical member that may employ the invention is a support post. The disclosure also relates to pump including such support posts and to other molten metal devices.

BRIEF DESCRIPTION OF THE DRAWINGS

10 FIG. 1 is a perspective view of a pump for pumping molten metal, which may include rotor shaft and plurality of support posts, in accordance with various embodiments.

15 FIG. 2A is a profile view of a support post, in accordance with various embodiments.

15 FIG. 2B is an exploded view of a support post, in accordance with various embodiments.

15 FIG. 3A is a cross sectional view of a support post, in accordance with various embodiments.

20 FIG. 3B is a cross sectional view of a bottom portion of a support post, in accordance with various embodiments.

20 FIG. 3C is a cross sectional view of a top portion of a support post, in accordance with various embodiments.

25 FIGS. 3D-3Z illustrate various components of exemplary support posts in accordance with various embodiments of the disclosure.

25 FIGS. 4A-4C illustrate a rotor plug in accordance with exemplary embodiments of the disclosure.

30 FIGS. 5A-1, 5A-2 and FIGS. 5B-5R illustrate a support post and various components thereof in accordance with additional exemplary embodiments of the disclosure.

30 FIGS. 6A-6J illustrate a rotor shaft and various components thereof in accordance with additional exemplary embodiments of the disclosure.

35 FIGS. 7A-7P illustrate a coupling and various components thereof in accordance with additional exemplary embodiments of the disclosure.

35 FIGS. 8A-8T illustrate a pump and various components thereof in accordance with exemplary embodiments of the disclosure.

DETAILED DESCRIPTION OF PREFERRED EMBODIMENTS

40 For any device described herein, any of the components 45 that contact the molten metal are preferably formed by a material that can withstand the molten metal environment. Preferred materials are oxidation-resistant graphite and ceramics, such as silicon carbide.

45 Reference will now be made in detail to the present 50 exemplary embodiments of the invention, examples of which are illustrated in the accompanying drawings. FIG. 1 depicts a molten metal pump 100 according to exemplary embodiments of the disclosure. When in operation, pump 100 is typically positioned in a molten metal bath in a pump 55 well, which is typically part of the open well of a reverberatory furnace. Pump 100 includes motor 120, superstructure 130, support shafts 140, drive shaft 122, rotor 110, base 160, and a gas transfer system 170. The gas transfer system 170 may comprise gas-transfer foot 172 and gas-transfer tube 174.

60 The components of pump 100 or portions thereof that are 65 exposed to the molten metal (such as support shafts 140, drive shaft 122, rotor 110, base 160, gas-transfer foot 172 and gas-transfer tube 174) are preferably formed of structural refractory materials, which are resistant to degradation in the molten metal.

65 Pump 100 need not be limited to the structure depicted in FIG. 1, but can be any structure or device for pumping or

otherwise conveying molten metal, such as the pump disclosed in U.S. Pat. No. 5,203,681 to Cooper, or an axial pump having an axial, rather than tangential, discharge. Preferred pump **100** includes a base **160** (e.g., a pump base) for being submersed in a molten metal bath. Pump base **160** preferably includes a generally nonvolute pump chamber **210**, such as a cylindrical pump chamber or what has been called a "cut" volute, although pump base **160** may have any shape pump chamber suitable of being used, including a volute-shaped chamber. Pump chamber **210** may be constructed to have only one opening, either in its top or bottom, if a tangential discharge is used, since only one opening is required to introduce molten metal into pump chamber **210**. Generally, pump chamber **210** has two coaxial openings of the same diameter and usually one is blocked by a flow blocking plate mounted on, or formed as part of, rotor **110**. Base **160** further includes a tangential discharge **220** (although another type of discharge, such as an axial discharge may be used) in fluid communication with pump chamber **210**.

In this embodiment, one or more support posts **140** connect base **160** to a superstructure **130** of pump **100** thus supporting superstructure **130**. Pump **100** could be constructed so there is no physical connection between the base and the superstructure, wherein the superstructure is independently supported. The motor, drive shaft and rotor could be suspended without a superstructure, wherein they are supported, directly or indirectly, to a structure independent of the pump base.

Motor **120**, which can be any structure, system or device suitable for driving pump **100**, but is preferably an electric or pneumatic motor, is positioned on superstructure **130** and is connected to an end of a drive shaft **122**. A drive shaft **122** can be any structure suitable for rotating an impeller, and preferably comprises a motor shaft (not shown) coupled to a rotor shaft. The motor shaft has a first end and a second end, wherein the first end of the motor shaft connects to motor **120** and the second end of the motor shaft connects to the coupling. Rotor shaft **124** has a first end and a second end, wherein the first end is connected to the coupling and the second end is connected to rotor (or impeller) **110**.

Rotor **110** can be any rotor suitable for use in a molten metal pump and the term "rotor," as used in connection with this disclosure, means any device or rotor used in a molten metal device to displace molten metal.

As described herein, support post (also referred to herein as support shaft) **140** may be a structure that is configured to support a motor and/or superstructure of a molten metal pump. In various embodiments and with reference to FIG. 2A and FIG. 2B, a support post **240**, suitable for use as support post **140**, comprises a tube **250**, a tension rod **242**, a bottom cap **246**, and a top cap **244**. Tension rod **242** may be disposed within a cavity **251** defined by the inner wall **149** of tube **250**. Tension rod **242** may be attached at one and to bottom cap **246** and at its other end to top cap **244**. In this embodiment, tension rod **242** is placed in tension by bottom cap **246** and top cap **244**, creating a compressive load on tube **250**.

Tube **250**, illustrated in more detail in FIGS. 3L-3N, preferably comprises a first end **250A** and a second end **250B**. Bottom cap **246** is configured to receive, engage, retain, and/or otherwise mate to the first end **250A** of tube **250**. Bottom cap **246** may also be operatively coupled to the first end **242A** of tension rod **242**. Top cap **244** may be configured to receive, engage, mate with, couple to, and/or otherwise receive the second end **250B** of tube **250**. Similarly, top cap **244** may be configured to operatively couple

to, engage, and/or otherwise mate with the second end **242B** of tension rod **242** and/or a portion of tension rod **242** adjacent to the second end **242B** of tension rod **242**.

In various embodiments, tube **250** may comprise inner or 5 interior surface **149** that defines a hollow channel or cavity **251** within tube **250**. As discussed herein, tension rod **242** may be installable within and/or housed by tube **250** within its hollow channel. Moreover, tension rod **242** may be separated from the interior surface of tube **250**. In this 10 regard, there may be a gap defined between tension rod **242** and the interior surface **149** of tube **250**.

In various embodiments, tube **250** may be a homogeneous 15 ceramic material. For example, tube **250** may be formed of a ceramic material such as, for example, silicon carbide.

FIGS. 3O-3Q illustrate tension rod **242** in greater detail. Tension rod **242** can be formed of, for example, steel. Exemplary tension rods have a length of about 38.75 to 20 about 45.75 inches and can have a diameter of about one inch. First end **242A** can include a flat face **242D**, while second end **242B** can include a tip that includes a first portion **242E**, which is cylindrical in shape and which has a smaller diameter than a middle section **242G**, and a second section **242F** that is frusto-conical in shape.

Top cap **244** and bottom cap **246** are preferably made of 25 graphite. In various embodiments, and with reference to FIG. 2B, bottom cap **246** is in the form of an assembly. Bottom cap **246** comprises a housing **247** and a cover **248**. Cover **248**, may be operatively coupled to and/or may be installable within housing **247**. For example, cover **248** may 30 comprise a threaded portion **272** that is configured to thread into or otherwise engage with a receivable channel or cylinder within housing **247**. Moreover, bottom cap **246** may comprise a fastener **254-1** and a washer **252-1**. Fastener **254-1** and/or washer **252-1** is configured to engage the first 35 end **242A** of tension rod **242**.

Bottom cap **246** and portions thereof are illustrated in 40 greater detail in FIGS. 3D-3K. Housing **247** includes a top portion **260** including a top surface **261** having a recess **262** formed therein for receiving tube **250**, a channel **264** for receiving tension rod **242**, and an opening **266** for receiving cover **248** through a bottom portion **268** of housing **247**. Recess **262**, and channel **264** and opening **266** can be coaxial. As illustrated in FIG. 3E, a portion of opening **266** 45 can be threaded, so as to enable engagement with threaded portion **272** of cover **248**. Housing **247** can also include a cavity **270**.

In various embodiments, top cap **244** is an assembly 50 comprising housing **243** and spring **256** (illustrated in more detail in FIGS. 3U-3W). Spring **256** is installable within housing **243** of top cap **244**. Second end **242B** of tension rod **242** is configured to pass through and protrude from housing **243** of top cap **244**. Spring **256** is installable over second end **242B** of tension rod **242**. In this regard, spring **256** is 55 preferably configured to add tension to rod **242**. Top cap **244** may further comprise a spring cover **257** (illustrated in more detail in FIGS. 3X-3Z), one or more washers including, for example, washer **252-2** and washer **252-3**, and a fastener **254-2**. Spring cover **257** as shown is installable over spring **256**. One or more washers such as, for example, washer **252-2** and washer **252-3** may be installable on either side of 60 spring cover **257**. In this regard, washer **252-2** and/or washer **252-3** are configured to retain spring **256** within spring cover **257**. Moreover, fastener **254-2** may be configured to engage and/or may be installable on the second end **242B** of tension rod **242**. Second end **242B** of tension rod **242** may comprise 65 a threaded portion **242C**. Fastener **254-2** may be configured to engage and/or may be installable on the threaded portion

242C. Fastener 254-2 may also be configured to seat against and/or retain one or more of washer 252-2, washer 252-3, spring 256, and/or spring cover 257. In this regard, the assembly within top cap 244 is preferably configured to create a load on tension rod 242 thus creating a compressive load on tube 250.

FIGS. 3R-3T illustrate housing 243 in greater detail. Housing 243 includes a first opening 274, a passage 276, and a second opening 278, all of which can be coaxial. Recess 243 can be configured to receive a portion of tube 250, passage 276 can be configured to receive tension rod 242 therethrough, and recess 274 can be configured to receive washer 252-2, spring 256, spring cover 257, washer 252-3, and fastener 254-2.

In various embodiments, and with reference to FIG. 3A, FIG. 3B, and FIG. 3C, a support post 340, which may be the same or similar to support post 240, may comprise portions that are self-contained. For example, bottom cap 346 may create a self-contained assembly when tube 350 is installed with and/or engages bottom cap 346. In this regard, bottom cap 346 may be configured to isolate a tension rod 342 from a molten metal environment when support post 340 is installed on a molten metal pump. In operation, portions of support post 340 would be submerged within a molten metal bath. In order to prevent corrosion of tension rod 342 (which can be the same as or similar to tension rod 242), tube 350 (which can be the same as or similar to tube 250) and bottom cap 346 may be configured to form a liquid tight assembly that prevents molten metal (e.g., molten aluminum) from reaching tension rod 342.

In various embodiments, and as discussed herein, bottom cap 346 may comprise various parts including washers such as, for example, washer 352-1 and fasteners such as, for example, fastener 354-1. These washers and fasteners may be separately removable components or they may be integrally formed within one or more components of bottom cap 346. For example, washer 352-1 may be integrally formed within housing 347. In this regard, a first end 342A of tension rod 342 may be configured to pass through housing 347 and/or washer 352-1. Moreover, the first end 342A of tension rod 342 may comprise a threaded portion 342C that threads into and/or threads through housing 347 and/or washer 352-1. Housing 347 and/or cover 348 may also comprise and/or may be configured with an integrally formed fastener 354-1. In this regard, first end 342A of tension rod 342 may be configured to thread through the integral fastener 354-1 and/or may be capable of having the integral fastener threaded on the threaded portion 342C of the first end 342A of tension rod 342.

In various embodiments, top cap 344 may be an assembly that is configured to receive a threaded portion 342D of a second end 342B of tension rod 342. Top cap 344 may comprise various components including, for example, washers 352-2 and 352-3, fastener 354-2, spring 356, and/or spring cover 357. One or more of these elements may be integrally formed within top cap 344. For example, washer 352-2 may be integrally formed within or as part of top cap 344. Moreover, top cap 344 may be a multi-piece assembly that allows for installation of various components including, for example, spring 356 and/or spring cover 357. Top cap 344 may be, for example, a clamshell assembly having two halves that thread together. A first portion 344A of the clamshell assembly of top cap 344 may comprise a washer 352-2 that is configured to provide a seat or loading surface for spring 356 and a seating surface for spring cover 357. Moreover, a second portion 344B of a clamshell assembly of top cap 344 may comprise an integrally formed fastener

354-2 and washer 352-3. In this regard, the first portion 344A and second portion 344B of the clamshell assembly of top cap 344 may be operatively coupled to one another with various fasteners, threading and/or the like.

5 In various embodiments, the second end 342B of tension rod 342 may comprise a threaded portion 342D that is configured to thread through and/or pass through one or more components of top cap 344, including, for example, spring 356, washers 352-2 and 352-3, spring cover 357, fastener 354-2, housing 343, and/or the like. In this regard, 10 the second end 342B of tension rod 342 may comprise a threaded portion 342D and a guide portion 342E having a tip with a reduced diameter and/or a chamfered edge.

In various embodiments, the second end 342B of tension rod 342 may pass through top cap 344 allowing engagement with a base or superstructure of a molten metal pump.

15 FIGS. 5A-5C illustrate a support post 540, also suitable as support post 140, in accordance with additional exemplary embodiments. Support post 540 includes a tube 550, a tension rod 542, a bottom cap 546, and a top cap 544. Tension rod 542 can be disposed within a cavity 551, which is defined by an inner wall 549 or tube 550.

20 FIG. 5D and FIGS. 5F-5H illustrate bottom cap 546 in greater detail. Bottom cap 546 includes a housing 548 to receive a first end 542A of tension rod 542. In the illustrated example, housing 548 includes a recess 551 to threadedly or otherwise engage with first end 542A of tension rod 542. As illustrated in FIG. 5H, recess 551 can include a substantially cylindrical section 560 and a conical section 562 that comes 25 to a point. Housing 548 also includes a recess 553 to receive a first end 550A of tube 550. Recesses 552 and 551 can be coaxial. As illustrated in FIG. 5G, recess 553 includes a tapered section 564 and a cylindrical section 566. Recess 553 includes a flat surface 555, having a hole therethrough 30 to receive first end 542A of tension rod 542.

25 Top cap 544, illustrated in greater detail in FIGS. 5E and 5O-5R, includes a housing 570 to receive a second end 542B of tension rod 542. In the illustrated example, housing 570 includes a recess 571 to threadedly or otherwise engage with second end 542B of tension rod 542. Recess 571 can include a first substantially cylindrical section 572, a second substantially cylindrical portion 573, and a conical section 574 that comes to a point 575. Housing 570 or top cap 544 also 30 include a recess 576 that includes a (e.g., flat) surface 577 that engages with and can contact second end 550B of tube 550. Top cap 544 can also include a notch on at least a portion of housing 570. Top cap 544 can also include a hole 580 extending partially or entirely through housing 570.

35 Top cap 544 and bottom cap 546 can be attached (e.g., threadedly) to second end 542B and first end 542A, respectively, of tension rod 542 to apply a compressive load to tube 550.

40 FIGS. 51-5K illustrate tube 550 in greater detail. Tube 550 includes a first cylindrical portion 582, a tapered portion 586, and optionally a second cylindrical portion 588. As illustrated in FIG. 5J, cavity 551 extends through portions 582, 586, and 588. Cavity 551 can be tapered, such that an opening at first end 550A is smaller than the opening of cavity 551 at second end 550B. For example, the opening at second end 550B can have a diameter of about 1.6 inches and the opening at first end can have a diameter of about 1.4 inches, when a length L of tube 550 ranges from about 27.9 to about 38.5 inches.

45 First end 550A of tube 550 includes tapered portion 586 and optional cylindrical portion 588. As illustrated in FIG. 5C, portions 586 and 588 can be received by housing 548 of bottom cap 546. First end 550A also include a face 590,

which can be flat or substantially flat, so as to engage (e.g., contact) surface 555 of bottom cap 546. Similarly, second end 550B includes a face 592 that can be flat and configured to engage with and/or contact surface 577 of top cap 544. A portion of first cylindrical portion 582 can be received within recess 576, so that face 592 contacts surface 577. Recess 576 can be, for example, about 3/4 inches thick with a diameter of about 5.05 inches.

FIGS. 5L-5N illustrate tension rod 542 in greater detail. As previously noted, tension rod includes first end 542A, which includes an engagement mechanism 594, such as threads. Similarly, second end 542B includes an engagement mechanism 596, such as threads. Engagement mechanisms 594 and 596 allow top cap 544 and bottom cap 546 to attach to tension rod 542, so as to allow a compressive force to be applied to tube 550. As illustrated, ends 542C and 542D or tension rod 542 can include a flat face that is perpendicular to the axis of tension rod 542.

FIGS. 6A-6J illustrate a rotor shaft in accordance with various embodiments of the disclosure. Rotor shaft 600 includes an outer tube 602, an inner rod 604, a cap 606, and a structure 618. Rotor shaft 600 is attached to a rotor 608.

Outer tube 602 includes a first end 610, a second end 612, and an outer surface 612. Outer tube 602 includes a cavity 614 spanning therethrough to receive inner rod 604. Outer tube 602 can be formed of, for example, a ceramic, such as silicon carbide.

Inner rod 604 can include a rod (e.g., steel) that is partially threaded—e.g., including first (e.g., threaded) portion 615 and second (e.g., threaded) portion 616. Structure 618, such as a nut, can be threadedly attached to second threaded portion 616 to retain rotor 608 proximate or adjacent second end 612. First portion 615 can be used to engage with cap 606 to retain cap 606 proximate or adjacent first end 610. Rotor shaft 600 can also include a washer 620—e.g., between rotor 608 and nut 618.

Cap 606 and portions thereof are illustrated in more detail in FIGS. 6D-6J. Cap 606 includes a first section 622 having a top section 623 configured to engage with a coupling (an exemplary coupling is described in more detail below) and a bottom section 624 configured to engage with outer tube 602 and inner rod 604. Top section 622 can be of substantially tubular shape, having one or more L-shaped openings 626 formed therein to connect cap 606 to a coupling. Bottom section 624 includes a cavity 626 to receive inner rod 604, a first recess 628 to receive a bottom portion of first section 622, and a third recess 630 to receive a top surface of first end 610 of outer tube 602. Cap 606 can be formed of, for example, steel. Further, cap 606 can be configured, such that when cap 606 is connected to a coupling and the coupling drives rotor shaft 600, rotor shaft 600 moves in a direction that tightens the cap against first end 610 of outer tube 602 to apply axial pressure on outer tube 602.

Rotor shaft 600 can also include a rotor plug 400, illustrated in FIGS. 4A-4C. Rotor plug 400 can be received by (e.g., threadedly) by rotor 608, as illustrated in FIG. 6B. Rotor plug 400 includes threads 402 to engage with rotor 608. Rotor plug 400 can also include recess 404 to facilitate threaded engagement of rotor plug with rotor 608.

Rotor 608 connects to second end 612 of rotor shaft 602. Rotor 608 includes one or more (e.g., a plurality) of spaced-apart blades 632-636, a passageway 638 for receiving second (e.g., threaded) end 616 of inner rod 604, a cavity for retaining structure 618 and for receiving rotor plug 400.

FIGS. 7A-7P illustrate a coupling 700 suitable for use with a rotor shaft for a molten metal device. Coupling 700 includes a body 702, one or more securing structures 704-

708, and one or more tightening structures 710,712, and 714. Coupling 700 can be used to couple rotor shaft 602 to, for example, a motor shaft (also referred to herein as a motor post). Each of the components of coupling 700 can be formed of steel (e.g., hardened steel).

Body 702 includes an opening 716 to receive a motor shaft from a motor, described in more detail below, and an outer surface 718 to be received by an inner surface 640 of cap 606 of rotor shaft 600. Body 702 also includes openings 720, 722 and 724 to receive (e.g., threadedly) one or more (e.g., manual) tightening structures 710-714. Body 702 also includes opening 726 and 728 to receive a rod 730, which can be a hardened steel rod having, for example a diameter of about 0.75 inches and a length of about 4.75 inches. Body 702 can further include a notch 732 and/or recessed region 734. In the illustrated example, opening 716 includes recessed region 734, a first section 736, and a second section 738. A diameter of the opening of recessed region 734 is larger than the diameter of the opening of first region 736, and the diameter of the opening of first region 736 is larger than a diameter of the opening of second region 738. Each of the recessed region 734, the opening in the first region, and the opening in the second region can be cylindrical.

Securing structures 704-708 can be in the form of tubes formed of, for example, schedule 40 pipe, having a one inch diameter (e.g., about 1.049" ID and about 1.315" OD) and a length of about 3.5 inches. Securing structures 704-708 can be welded to outer surface 718—e.g., evenly spaced along the same height of outer surface 718. In the illustrated example, three securing structures 704-708 are welded to outer surface 718.

FIGS. 8A-8T illustrate a pump 800 in accordance with various embodiments of the disclosure. Pump 800 can be similar to pump 100, and similar to pump 100, pump 800 can be used for circulation or as a degasser or for demagging. Pump 800 includes a base assembly 802, one or more support posts 806-808, a rotor shaft 810, an injection button 812, an injection tube 814, a pump mount assembly or superstructure 816, a washer 818 and a lock washer 820, an injection tube clamp 822, a motor 824, a coupling 826, a motor strap 828, fasteners (e.g., bolts) 830-836 and (e.g., nuts) 838-844 and a fastener 846. Similar to pump 100, components of pump 800 that are exposed to molten metal can be formed of structural refractory materials, such as ceramic or graphite, that are resistant to degradation in the molten metal.

Pump mount assembly 816 includes a pump mount 846, pump mount insulation 848, a motor mount plate 849, one or more fasteners 850, such as bolts 852 and washers (e.g., lock washers) 854. Pump mount insulating 848 can be coupled to pump mount 846 using, for example, bracket 849 and fastener 851, which can include, for example, a bolt 853 and a washer 855. Motor mount plate 849 can be attached to pump mount 846 using fasteners 850.

Base assembly 802 includes a pump chamber 856 that can include any suitably shaped chamber, such as a generally nonvolute shape—e.g., a cylindrical pump chamber, sometimes referred to as a “cut” volute; alternatively pump chamber 856 can include a volute-shape. Pump chamber 856 can be constructed to have only one opening, either in its top or bottom, if a tangential discharge is used, since only one opening is required to introduce molten metal into pump chamber 856. Pump chamber 856 can include two coaxial openings of the same diameter, in which case usually one is blocked by a flow blocking plate 803 mounted on, or formed as part of, rotor 801. Base assembly 802 further includes a tangential discharge 858 (although another type of dis-

11

charge, such as an axial discharge may be used) in fluid communication with pump chamber 856.

The one or more support posts 806-808 can be the same or similar to support posts described elsewhere herein. For example, support posts 806-810 can be support posts 140, 240, 340, or 540. Similarly, rotor shaft 810 can be the same as or similar to rotor shaft 600.

Injection button 812 can be coupled to injection tube 814. Injection tube 814 can, in turn, can be coupled to pump mount assembly 816 or another portion of pump 800 using, for example, injection tube clamp 822. Injection button 812 and injection tube 814 can be used to provide gas from a gas source to a molten metal bath, wherein injection button 812 is at least partially within the molten metal bath. The gas can be released downstream of pump chamber 856 into the pump discharge or into a stream of molten metal exiting wither the discharge or a conduit. Alternatively, gas can be released into pump chamber 856 or upstream of pump chamber 856. FIGS. 8D-8M and 8T illustrate various configurations of pump 800.

Some specific examples of embodiments of the invention follow:

1. A support post, comprising:

a tube defining a hollow channel and having a first tube end and a second tube end;

a tension rod having a first rod end and a second rod end disposed within the hollow channel of the tube;

a bottom cap configured to receive the first tube end and operatively coupled to the first rod end; and

a top cap configured to receive the second tube end and operatively couple to a portion of the tension rod, wherein the tension rod is configured to load the tube in response to be operatively coupled to the bottom cap and the top cap.

2. The support post of example 1, wherein the tube is a homogenous ceramic.

3. The support post of example 1, wherein the tube is silicon carbide.

4. The support post of example 1, wherein the tube is comprised of silicon carbide.

5. The support post of any of examples 1-4, wherein the tube comprises an interior surface, and wherein the tension rod is separated from the interior surface defining a gap between the tension rod and the interior surface.

6. The support post of any of examples 1-5, wherein the bottom cap is made of graphite.

7. The support post of any of examples 1-5, wherein the bottom cap and top cap are each comprised of one or more of graphite and silicon carbide.

8. The support post of any of examples 1-7 further comprising a fastener disposed within the bottom cap and configured to engage the tension rod to retain the tension rod within the bottom.

9. The support post of example 8, wherein a portion of the tension rod adjacent the first rod end is threaded and configured to receivably engage the fastener.

10. The support post of example 7 or 8 further comprising a washer installable over the first rod end of the tension rod and engagable by the fastener, wherein the fastener is configured to load the tension rod.

11. The support post of any of examples 1-10, wherein the bottom is a two-piece assembly that is configured to isolate the tension rod from a molten metal environment.

12. The support post of any of examples 1-11, further comprising a spring disposed within the top cap and installable over the second rod end.

13. The support post of example 12, wherein the spring is configured to load the tension rod.

12

14. The support post of example 12, further comprising a first washer, a second washer, and a fastener, wherein the spring is disposed between the first washer and the second washer and retained by the fastener within the top cap.

15. The support post of example 14, a portion of the tension rod adjacent the second rod end is threaded and is configured to receive the fastener.

16. The support post of any of examples 1-15, wherein the second rod end is configured to protrude through the top cap.

17. A molten metal pump comprising:

a superstructure;

a motor having a motor post with a first post end connected to the motor and a second post end;

a rotor shaft operatively coupled to the second post end;

18. A support post comprising,

a tube defining a hollow channel;

a tension rod having a first rod end and a second rod end disposed within the hollow channel of the tube;

a bottom cap operatively coupled to the first rod end; and

a top cap operatively coupled to a portion of the tension rod, wherein the tension rod is configured to load the tube in response to be operatively coupled to the bottom cap and the top cap; and

a base coupled to the superstructure by the support post.

19. A molten metal pump comprising:

a superstructure;

a motor having a motor post with a first post end connected to the motor and a second post end;

a rotor shaft operatively coupled to the second post end;

20. A plurality of support posts, each of the plurality of support posts comprising,

a tube defining a hollow channel;

a tension rod disposed within the hollow channel of the tube;

a bottom cap operatively coupled to the tension rod; and

21. A base coupled to the superstructure by the plurality of support posts.

22. A molten metal pump containing one of the support posts of examples 1-17.

23. A rotor shaft for use in a molten metal device, the rotor shaft comprising:

24. an outer tube having a first end, a second end, and an outer surface;

25. an inner rod having a first end and a second end;

26. a cap that threads onto the first end of the inner rod, and that has an upper portion configured to be connected to a coupling that drives the rotor shaft; and

27. a structure that retains the second end of the outer tube; wherein when the cap is connected to the coupling and the coupling drives the rotor shaft, the rotor shaft moves in a direction that tightens the cap against the first end of the outer tube to apply axial pressure on the outer tube.

28. The rotor shaft of example 20 wherein the outer tube is comprised of ceramic.

29. The rotor shaft of example 21 wherein the ceramic is silicon carbide.

30. The rotor shaft of any of examples 20-22 wherein the structure that retains the second end of the outer tube is a nut threaded onto the second end.

31. The rotor shaft of example 23 that further includes a washer on the second end.

32. The rotor shaft of any of examples 20-23 that further includes a rotor and a rotor plug received in the bottom of the rotor.

13

26. The rotor shaft of any of examples 20-25 wherein the upper portion of the cap includes one or more L-shaped openings to connect to the coupling.
27. A rotor for being connected to a rotor shaft used in a molten metal device, the rotor comprising a plurality of spaced-apart blades, a passageway for receiving the second end of a rotor shaft according to any of examples 20-24 or 26, and a cavity for retaining a structure that retains the second end of the rotor shaft.
28. The rotor shaft of example 27 wherein the structure is a nut threadingly received on the second end.
29. The rotor shaft of either of examples 27-28 that further includes a rotor cap on a bottom of the rotor, the cap for covering the cavity.
30. A coupling for use with a rotor shaft for a molten metal device, the coupling comprising:
- a body including an opening for receiving a rotor shaft, and
  - one or more securing structures to retain the rotor shaft in the opening;
  - one or more manual tightening structures on the outer surface.
31. The coupling of example 30 that has two tightening structures.
32. The coupling of any of examples 30-31 wherein the tightening structures are bolts threaded through the body of the coupling.
33. The coupling of any of examples 30-32 wherein the manual tightening structures are tubes welded to the outer surface.
34. The coupling of any of examples 30-33 that is comprised of steel.
35. The coupling of any of examples 30-34 wherein the opening is cylindrical.
36. The coupling of any of examples 30-35 that further includes two openings for receiving a through bolt.
37. The coupling of example 36 that further includes a through bolt.
38. A molten metal pump comprising the coupling of any of examples 30-37.
39. A rotary degasser comprising the coupling of any of examples 1-37.
40. The rotor shaft of example 23 wherein the nut is retained inside of a rotor.
41. The rotor shaft of example 24 wherein the nut and washer are retained inside of a rotor.

Having thus described different embodiments of the invention, other variations and embodiments that do not depart from the spirit of the invention will become apparent to those skilled in the art. The scope of the present invention is thus not limited to any particular embodiment, but is instead set forth in the appended claims and the legal equivalents thereof. Unless expressly stated in the written description or claims, the steps of any method recited in the claims may be performed in any order capable of yielding the desired result. Further, any dimensions provided herein are provided for reference only. Unless otherwise stated, the invention is not limited to components having such dimensions.

What is claimed is:

1. A rotor shaft for use in a molten metal device, the rotor shaft comprising a first end, a second end, and further comprising:
  - (a) a hollow outer tube having a first end at the first end of the rotor shaft, a second end at the second end of the rotor shaft, a tube body, and an outer surface;

14

- (b) a tension rod having a first end at the first end of the rotor shaft and a second end at the second end of the rotor shaft;
  - (c) a cap threaded onto the first end of the tension rod, wherein the cap has an upper portion configured to be connected to a coupling that drives the rotor shaft; and
  - (d) a structure that retains the second end of the tension rod and the second end of the outer tube;
- wherein when the cap is connected to the coupling and the coupling drives the rotor shaft, the rotor shaft moves in a direction that tightens the cap onto the first end of the tension rod to apply axial pressure to the first end of the outer tube.
2. The rotor shaft of claim 1, wherein a fastener is threaded onto the second end of the tension rod.
  3. The rotor shaft of claim 2 that further comprises a washer on the second end of the tension rod.
  4. The rotor shaft of claim 1, wherein the tension rod is formed of steel.
  5. The rotor shaft of claim 1, wherein the upper portion of the cap comprises one or more L-shaped openings configured to connect to the coupling.
  6. The rotor shaft of claim 1, wherein the cap is comprised of steel.
  7. The rotor shaft of claim 1, wherein the cap is comprised of one or more of graphite and silicon carbide.
  8. The rotor shaft of claim 1, wherein the second end of the rotor shaft is configured to be attached to a rotor.
  9. The rotor shaft of claim 8, wherein the second end of the rotor shaft is connected attached to the rotor.
  10. The rotor shaft of claim 8, wherein the second end of the rotor shaft is threaded.
  11. The rotor shaft of claim 1, wherein the outer tube comprises one or both of ceramic and graphite.
  12. The rotor shaft of claim 1, wherein the outer tube comprises silicon carbide.
  13. The rotor shaft of claim 1, wherein the outer tube further comprises an interior surface, the tension rod is separated from the interior surface and there is a space between the tension rod and the interior surface.
  14. The rotor shaft of claim 9, wherein the rotor is comprised of graphite.
  15. The rotor shaft of claim 9, wherein the second end of the rotor shaft is connected to the rotor by a threaded connection.
  16. The rotor shaft of claim 9, wherein the rotor is configured to isolate the second end of tension rod from a molten metal environment.
  17. The rotor shaft of claim 16, wherein the rotor further comprises a cavity in which the second end of the tension rod is positioned.
  18. The rotor shaft of claim 16, wherein the second end of the tension rod is connected to the rotor by a threaded connection.
  19. The rotor shaft of claim 16 that further comprises a rotor plug received in the bottom of the rotor, wherein the rotor plug is configured to keep molten metal out of a cavity of the rotor.
  20. The rotor shaft of claim 9, wherein the rotor comprises a passageway for receiving the second end of the rotor shaft, and a cavity for retaining a structure that retains the second end of the tension rod in the cavity.
  21. The rotor shaft of claim 20, wherein the structure is a nut threadingly received on the second end of the tension rod.
  22. A molten metal pump comprising the rotor shaft of claim 1.

23. The molten metal pump of claim 22 that further comprises:

- (a) a superstructure;
- (b) a motor having a motor shaft with a first end connected to the motor and a second end connected to a coupling; 5
- (c) the coupling having a second end that is connected to the rotor shaft;
- (d) one or more support posts having a first end connected to the superstructure, and;
- (e) a base connected to a second end of each of the one or 10 more support posts.
